UNITED STATES PATENT OFFICE.

TALBOT C. DEXTER, OF PEARL RIVER, NEW YORK, ASSIGNOR TO THE DEXTER FOLDER COMPANY, OF NEW YORK, N. Y.

SHEET ASSEMBLING AND STAPLING MACHINE.

SPECIFICATION forming part of Letters Patent No. 595,941, dated December 21, 1897.

Application filed March 6, 1895. Renewed March 27, 1897. Serial No. 629,573. (No model.)

To all whom it may concern:

Be it known that I, TALBOT C. DEXTER, of Pearl River, in the county of Rockland, in the State of New York, have invented new and useful Improvements in Paper Folding and Stitching Machines, of which the following, taken in connection with the accompanying drawings, is a full, clear, and exact description.

The object of this invention is to provide a convenient and efficient machine which shall accurately and expeditiously fold together a plurality of sheets, each of which contains duplicates of printed matter, and to bind therewith a duplicate paper cover and separate the folded and bound duplicates during a single passage of the same through the machine.

The invention is more specially designed to fold what is termed a sheet of "two eight-page signatures" together with an insert-sheet of "two four-page signatures" and bind therewith a covering-sheet and to deliver the two copies separately into the packing-box of the machine; and to that end the invention consists in the novel organization of the paper folding, assembling, binding, and separating mechanisms, as hereinafter described, and specially set forth in the claims.

In the annexed drawings, Figure 1 is a side elevation of a machine embodying my invention. Figs. 2 and 3 are enlarged plan views of the machine, extending from the center to opposite ends of the machine. Fig. 4 is an enlarged vertical transverse section on line X X in Fig. 1, viewed in the direction of the arrow shown thereat. Fig. 5 is an enlarged end elevation viewed in the direction in which the main sheet is fed to the machine. Fig. 6 is an enlarged diagrammatic side view of the means for assembling and alining the plurality of sheets fed to the machine from different parts thereof. Fig. 7 is an enlarged detail view of one of the means for actuating the paper-alining gages by the drop-roller, and Fig. 8 is a vertical longitudinal sectional view of the mechanism for feeding the insert-sheet and cover to the main tapes.

Similar letters of reference indicate corresponding parts.

A represents the supporting-frame, which is formed with an elevated portion A', extend-

ing from one end some distance the length of the subjacent main portion.

R R represent two folding-rollers mounted on the elevated portion of the frame to receive by the paper-conveying tapes a a the sheets fed to the machine from the feed-board B on the rear end of said portion of the frame. This feed-board I designate the "main" feed-board in contradistinction to the tributary feed-boards B' and B", hereinafter described.

From the feed-board B is fed the main sheet or sheet of two eight-page signatures, which by means of the folding-rollers R R receives its first fold. In said transit of the sheet to the folding-rollers said sheet is arrested and alined by the usual gage b preparatory to folding the sheet. The sheet is introduced into the bite of the rollers by the usual blade C, attached to the intermittently-oscillating arms C'. Beneath the said folding-rollers are the paper-conveying tapes c, which I term the "main" tapes in contradistinction to certain tributary tapes, hereinafter referred to. All of said tapes run on suitable rollers in the usual manner and receive longitudinal motion by a train of gears. (Indicated by dotted lines in Fig. 1 of the drawings.) In the path of the said main tapes c c at opposite sides of and equidistant from the center of said path I place two wire stapling or stitching machines D D, which are both on the same line at right angles to the path of the tapes and in a plane to receive between the paper-supporting tables d and staple-drivers d' of said machines the paper carried on the tapes. These stitching-machines may be of any suitable and well-known construction, the details of which are not essential to my present invention and need not be illustrated. Fig. 4 of the drawings partly shows the cam e and eccentric e', which oscillate the staple-forming and staple-driving levers f f' of the species of stitching-machines selected for exemplification of the general operation of my invention.

A short distance in front of the two stitching-machines are gages g g, (see Fig. 6,) to which are delivered by means of the tributary tapes c' c" the main sheet folded by the rollers R R, as hereinbefore stated. The

tapes *c'* are carried on one of the folding-rollers and on pulleys *E*, which latter are mounted on a shaft extending across the machine and journaled in bearings on the elevated portion 5 *A'* of the frame. The other tapes *c'* are carried on rollers *i*, *i'*, and *i''*, so arranged as to cause said tapes to receive the folded main sheet from the tapes *c'* and deliver said sheet to the gages *g*, by which its movement is temporarily arrested. To properly deliver the sheet to said gages and support the tail portion of said sheet raised sufficiently from the main tapes *c c'*, so as to allow the tributary sheets hereinafter referred to to enter underneath the folded main sheet, I place adjacent to the roller *i'* a stationary inclined apron *h*, as more clearly shown in Fig. 6 of the drawings.

To the opposite end of the main frame *A* 20 I connect the tributary feed-board *B'*, upon which to feed to the machine the covers designed to be applied to the printed sheets. From this tributary feed-board to the main tapes *c c'* lead the tributary tapes *c'''*, carried 25 on rollers *j j'*. The roller *j* adjacent to said feed-board receives rotary motion from the train of gears hereinbefore referred to, and over said roller are drop-rollers *j''*, which intermittently press the sheet upon the subjacent rotary roller and thereby cause the sheet to be carried along by the tapes *c'''* in the usual and well-known manner. At the roller *j'* are 30 gages *g'*, which serve to temporarily arrest the movement of the cover-sheet fed from the tributary board *B'*. In front of this tributary feed-board is a supplemental tributary feed-board *B''*, upon which to feed to the machine the printed insert-sheet designed to be bound with the folded main sheet. Said insert-sheet 35 is carried from the feed-board *B''* to the gage *g'*, where it meets with the covering-sheet delivered to said gage in advance of the insert-sheet. This transmission of the insert-sheet is effected by means of endless tapes carried 40 on a series of transverse rollers *l l*, pivoted to arches *II*, extending from the delivery end of the feed-board *B''* to the frame *A*. Said rollers are thus supported at a proper elevation above the tributary feed-board *B'* to permit 45 convenient manipulation of the sheet fed from the latter board.

The tape-carrying roller *l''* over the end of the frame *A* receives positive rotary motion from the train of gears before mentioned, and 50 thus the tapes *l* receive longitudinal motion.

A drop-roller *K*, pressing the sheet upon a rotary roller *K'* at the delivery end of the feed-table *B''*, serves to carry the sheet to the conveying-tapes *l'*.

55 Over the gages *g'* are drop-rollers *K''*, which in their dropping motion lift the said gages, as represented in Fig. 7 of the drawings. These gages are attached to a transverse shaft *v*, pivoted at its ends to suitable supports on the sides of the frame *A*. The heels of said gages are provided with shoulders *v'*, and directly over these shoulders are cams *w'*, fas-

tened to the rock-shaft *w*, to which are secured the arms *w'*, carrying the shaft of the drop-rollers *K''*. The downward pressure of the said cams upon the shoulders *v'* during the descent of the drop-rollers lifts the gages *g'* out of the path of the paper. Said lifting of the gages liberates the sheets delivered as aforesaid, and the dropping of the rollers *K''* onto the sheets presses said sheets down upon the traveling tapes *c*, by which said sheets are carried to the gage *g*, and in this movement they pass under the folded main sheet previously delivered to said gage, as hereinbefore described. By means of said gage *g* all the sheets are assembled and aligned preparatory to passing to the stitching-machines *D*. In order to maintain the said sheets in their properly-assembled condition during their transit from the aforesaid gage to the stitching-machines and also during the operation of stitching or stapling the sheets, I employ intermittently-revolving rollers with drop-rollers over them and receiving between them the assembled sheets in their aforesaid transit. Said rollers are timed in their movements so as to first admit the sheets between them, then clamp the sheets while the rollers are deprived of rotation, and thereby temporarily arrest their progress without disturbance of their assembled condition, then release the sheets and propel them to their requisite position in relation to the stitching-machines to be stitched or stapled thereby and firmly hold the sheets in their latter position during the operation of stitching the same.

At the gages *g* is a roller *n*, placed with the top of its periphery in the plane of the upper run of the tapes *c* and at right angles to the tapes. This roller receives intermittent rotary motion by means of a ratchet-wheel *n'*, attached to the end of the shaft of said roller. A pawl *n''*, connected to a plate *o*, pivoted to the aforesaid shaft, engages said ratchet-wheel. To said plate is fastened a pinion *o'*, with which engages a rack *o''*, attached to a pitman *o'''*, which receives reciprocating motion by means of a roller *m*, pivoted to the pitman and held in contact with a rotary duplex cam *L* by a spring-actuated rod *m'*, connected to the pitman and sliding in an eye on the frame *A*. Said cam imparts two complete reciprocating motions to the pitman during each revolution of the cam for the purpose hereinafter explained. Over the roller *n* are drop-rollers *N*, which intermittently drop onto the sheets riding on the roller *n* and are held in elevated positions while the sheets approach the gages *g*, which are in position to arrest the sheets. The rollers *N* then drop onto the sheets and move the gages beneath the path of the sheets. This movement of the gage is effected by couplings *X*, connecting arms *X'* and *X''*, secured, respectively, to the shaft *y*, to which the gages are attached, and to the rock-shaft *y'*, to which the lifting-arms *y''* of the drop-rollers are attached.

The motion of the duplex cam *L* is so timed

as to retract the rack o'' and thus leave the roller n dormant when the rollers N drop onto the sheets. This is an important feature of my invention in that it prevents disturbance 5 of the sheets and serves to maintain them in adjustment. If the rollers were rotated when the drop-rollers press the plurality of sheets onto the roller n , the sheets would be liable to be disturbed from their alinement by the 10 frictional contact with the traveling surfaces of the rollers. As soon as the drop-rollers are brought to bear on top of the sheets the cam L pushes the rack o'' forward and thereby rotates the roller n , which, in conjunction with 15 the continuously-traveling tapes c , moves the sheets forward while the drop-rollers press upon the sheets. Said movement of the roller n advances the sheets just far enough to place 20 them in proper position at the stitching-machines $D D$ to receive therefrom the first staples. As soon as the sheets have arrived at 25 said position the cam L retracts the rack o'' , and in said movement the roller n remains at rest. This stationary roller, with the drop-rollers N pressing upon the sheets, causes the 30 latter to be retained in their position during the operation of the stitching-machines in applying the staples to the sheets. By the time the stapling is effected the cam L again pushes 35 the rack o'' forward and thereby sets the roller n in motion, which roller, in conjunction with the traveling tapes c , moves the sheets to the gages q , which is in a position to arrest the movement of the sheets, so as to hold the 40 same in position for receiving the second staples. The drop-rollers N bear on the sheets during said movement. This method of clamping the sheets between the revolving rollers n N during the operation of placing 45 the sheets in their requisite positions for being operated on by the stitching-machines D is very important, inasmuch as it positively moves the sheets to their said positions and retains the sheets in proper alinement during 50 said movements. While the sheets are held by the gage q the stitching-machines $D D$ apply the second staples to the sheets. The sheets are thus bound together along two parallel lines, which are respectively in range 55 with the bites of the two sets of folding-rollers $R' R'$, which subsequently fold the sheets after they are divided. These bound duplicate-printed sheets are severed by suitable rotary cutters $p p$; arranged between the stitching-machines D and folding-rollers R' and in a line 60 passing midway between the stitching-machines. The sheets are carried to said cutters by the following mechanism: At the gage q is another intermittently rotary roller q' , mounted 65 on a transverse shaft and arranged between the tapes $c c$ and immediately under the plane thereof and actuated by a rotary single cam s' , which, with the aid of a retracting-spring, imparts reciprocating motion to the rack s , engaging the pinion r'' , attached to a plate r' , which is pivoted to the shaft of the roller q' . A pawl r , connected to the plate r' , engages

the ratchet q'' , attached to the roller-shaft. Over the roller q' are drop-rollers N' , which are held in elevated positions during the approach of the sheets to the gages q . These gages are coupled to the rock-shaft Z of the drop-rollers N' in the same manner as the gages g , hereinbefore described, and are thus caused to release the sheets simultaneously 70 with the descent of the drop-rollers, and as soon as this takes place the cam s' imparts rotary motion to the roller q' , which, in conjunction with the traveling tapes c , move the sheets to the bite of the cutters $p p$, which 75 are fastened to rotary shafts extending across the machine. To these shafts are also attached rubber friction-rollers $p' p'$, as shown in Fig. 3 of the drawings. The gripping of the paper between the said rotating upper 80 and lower rollers carries the divided sewed portions of the paper to the folding-rollers $R' R'$, which are disposed parallel with the tapes $c c$ and with the bites of the rollers in lines with the rows of stitches. A gage t at 85 the farthest ends of said folding-rollers arrests the movement of the divided sheets, which are then tucked between the rollers by the usual folding-blades t' . A packing-trough u of any suitable or well-known form under 90 the latter folding-rollers receives the two copies properly folded and bound with a cover during the passage of the sheets through the machine in the before-described manner. 95

It is obvious that all the actuating mechanisms of the rollers which control the movements of the assembled sheets to the stitching-machine must be located outside of the frame of the machine, as shown in Fig. 3 of the drawings, in order to prevent their interference with the travel of the said sheets. 100

What I claim as my invention is—

1. A combined paper folding and stitching machine comprising main paper-conveying tapes, tributary conveyers delivering a plurality of sheets to said tapes, a stitching-machine in the path of the main tapes, a gage assembling and alining the sheets on the main tapes in front of the stitching-machine, rollers immediately under the plane of the tapes 110 at the aforesaid gage, drop-rollers over the aforesaid rollers and mechanism imparting intermittent motion to the rollers and timed to stop said motion simultaneously with the descent of the drop-rollers to prevent disturbance of the assembled sheets and subsequently rotate said rollers to pass said sheets 115 collectively and in their alined condition to the stitching-machine as set forth. 120

2. In combination with a set of main paper-conveying tapes, a wire-stitching machine in the path of said tapes, a plurality of tributary conveyers carrying sheets from different sources to the main conveying-tapes, movable gages in front and rear of the stitching-machine to aline the sheets in transit, and drop-rollers releasing the sheets from the gages 130 and impelling the sheets to and from the stitching-machine as set forth. 125

3. In combination with a set of main carrying-tapes, a plurality of feed-boards located at different parts of the machine, paper-folding rollers receiving the sheets from one of 5 said feed-boards, tapes conveying the folded sheets from said rollers to the main conveying-tapes, separate sets of tapes carrying the sheets from the other feed-boards to the main tapes back of the delivery of the folded sheet, 10 a gage gathering and alining the several sheets upon the main tapes, and a wire-stitching machine in the path of the main tapes receiving and stapling the gathered sheets as set forth.

4. In combination with a set of main conveying-tapes, a wire-stitching machine in the 15 path of said tapes, tributary sets of tapes delivering sheets to the main conveying-tapes at different distances from the stitching-machine, an alining-gage at the rearmost point 20 of said delivery, and a gage in front of the stitching-machine and in proximity thereto to collect all the sheets from the aforesaid deliveries and aline said sheets preparatory to being acted upon by the stitching-machine as 25 set forth and shown.

5. In combination with a set of main conveying-tapes, two wire-stitching machines at opposite sides of the center of the path of said tapes, a main feed-board and tributary feed- 30 boards at different parts of the machine, folding-rollers receiving the sheets from the main feed-board, tapes conveying the folded sheets from said rollers to the aforesaid main tapes in front of the stitching-machines, tapes carrying sheets from the tributary feed-boards to the main tapes back of the delivery of the folded sheet, a sheet-alining gage at the delivery of the tributary sheets, a gage at the delivery of the folded sheet collecting and 35 alining all the delivered sheets preparatory to being acted on by the stitching-machines, a cutter dividing the sheets, between the lines of stitches, two sets of folding-rollers folding the divided sheets, and a gage arresting the 40 sheets preparatory to entering between said rollers as set forth.

6. In combination with the set of main tapes and two wire-stitching machines at opposite sides of the center of the path of said tapes, 45 a plurality of tributary tapes delivering sheets from different parts of the machine to said main tapes, movable gages in front of the stitching-machines collecting and alining the group of sheets preparatory to being stitched, 50 a ratchet-wheel attached to one of the main-tape rollers, a pinion pivoted to the axis of said roller, a plate attached to said pinion, a pawl connected to said plate and engaging the ratchet-wheel, a rack engaging the pinion, a 55 rotary cam imparting reciprocating motion to the rack, and drop-rollers over the aforesaid tape-carrying roller as set forth.

7. In combination with the main tapes, two wire-stitching machines at opposite sides of 60 the center of the path of said tapes, tributary tapes delivering sheets from different parts of the machine to said main tapes in

front of the stitching-machines, a gage alining the sheets thereat, intermittently-operating sheet-propellers in front and rear of the 70 stitching-machines and timed with the stitching-machines to arrest the movements of the sheet to stitch the latter at different points along the line of their travel as set forth.

8. In combination with the set of main 75 tapes, two wire-stitching machines at opposite sides of the center of the path of said tapes and in a line at right angles to said path, feed-boards at different parts of the machine, folding-rollers receiving the sheet 80 from one of said feed-boards, tapes delivering the folded sheet from said rollers to the main tapes in front of the stitching-machines, tapes conveying tributary sheets to the main tapes in front of the delivery of the folded sheet, 85 gages arresting and alining the group of sheets preparatory to being stitched, intermittently-operating sheet-propellers in front and rear of the stitching-machines and timed to arrest the movement of the sheets to be repeatedly acted upon by the stitching-machines, a cutter severing the stitched sheets along the line central between the rows of stitchings, and two sets of folding-rollers receiving the severed sheets as set forth. 90

9. In combination with the main tapes, two wire-stitching machines at opposite sides of the center of the path of said tapes, a main feed-board over one end of the machine, folding-rollers receiving the sheet from said feed-board, tapes conveying the folded sheet to the main tapes in front of the stitching-machines, a tributary feed-board at the opposite end of the machine, a supplemental feed-board in front of said tributary feed-board, 100 tape-carrying rollers supported in an arc over the latter feed-board and conveying the sheet from the supplemental feed-board to the delivery end of the tributary feed-board, tapes leading from the tributary table to the aforesaid main tapes and carrying jointly the sheets fed from the top feed-board at said end of the machine, gages alining said sheets on the main tapes in front of the delivery of the folded sheet, gages arresting and alining 105 all of said sheets in front of the stitching-machines, an intermittently-rotating roller carrying the group of sheets to the stitching-machines to receive a plurality of stitches, a cutter severing the stitched sheets along a 110 line central between the rows of stitches, an intermittently-rotating roller passing the stitched sheets to said cutter, and two sets of folding-rollers receiving the divided sheets as set forth. 115

10. A machine for folding, binding, and separating sheets containing duplicate signatures comprising a set of main paper-conveying tapes, two stitching or stapling machines disposed at opposite sides of the center of the lines of travel of said tapes, a plurality of tributary tapes carrying the duplicate sheets to said main tapes, a gage assembling and alining said sheets in transit 120 125 130

to the stitching or stapling machines, mechanisms operating consecutively to arrest the assembled sheets and hold the same in position to receive the stitching or stapling at different points in the lengths of the sheets, a cutter separating the two stitched or stapled sheets central between the lines of stitching or stapling, and two sets of folding-rollers folding the separated sheets as set forth.

11. A paper folding and stitching machine consisting of main conveying-tapes, two stitching-machines at opposite sides of the center of the line of travel of said tapes and in line with each other and at right angles to the tapes, a feed-board for the reception of the duplex-signature sheets, rollers folding said sheet across its center, tapes conveying said folded sheet to the aforesaid main tapes, gages arresting said sheet at the rear of the stitching-machines, tributary feed-boards for the reception of the insert-sheet and the covering-sheet, tapes conveying the latter two sheets to the aforesaid gages and assembling them with the folded main sheet, an intermittently rotary roller extending across the machine directly under the main tapes at the aforesaid gages, drop-rollers over the aforesaid roller, a coupling between the drop-rollers and gages to remove the latter from the

path of the paper simultaneously with the dropping of the rollers, mechanism imparting rotary motion to the lower roller and timed to arrest the motion simultaneously with the descent of the drop-rollers and thereby clamp the assembled sheets between the rollers and subsequently rotate the rollers to advance the assembled sheets to a position to receive the first staples from the stitching-machines and while in this position arrest the motion of the rollers to clamp and hold the sheets stationary in their assembled condition, and then again rotate said rollers to advance said sheets, a similar set of gages and rollers beyond the stitching-machines arresting and holding the aforesaid sheets while receiving the second staples and subsequently propel the stitched sheets, a cutter separating the stapled sheets on a line central between the stitching-machines, and folding-rollers receiving the separated sections of the stitched sheets as set forth.

In testimony whereof I have hereunto signed my name this 14th day of February, 1895.

TALBOT C. DEXTER. [L. S.]
